Primary Examiner — Natasha Vujcic*Assistant Examiner* — Gilbert B Ford(74) *Attorney, Agent, or Firm* — Budzyn IP Law, LLC(57) **CLAIM**

The ornamental design for a blood collection safety needle, as shown and described.

DESCRIPTION

FIG. 1 is a perspective view of a blood collection safety needle;

FIG. 2 is a front elevation view thereof;

FIG. 3 is a rear elevation view thereof;

FIG. 4 is a right side elevation view thereof;

FIG. 5 is a left side elevational view thereof;

FIG. 6 is a top plan view thereof; and,

FIG. 7 is a bottom plan view thereof.

The broken lines in the figures illustrate portions of the blood collection safety needle which form no part of the claimed design.

1 Claim, 4 Drawing Sheets(56)
